UNITED STATES PATENT OFFICE.

SELDEN S. DAVIS, OF SOUTH PASADENA, CALIFORNIA.

SPARK PLUG.

Application filed May 7, 1923. Serial No. 337,378.

To all whom it may concern:

Be it known that I, SELDEN S. DAVIS, a citizen of the United States, and a resident of South Pasadena, county of Los Angeles, 5 State of California, have invented a new and useful Spark Plug, of which the following is a specification.

The present invention relates to improvements in spark plugs such as are commonly used for igniting a charge in an internal combustion engine. The particular object of the invention is to provide a spark plug that will give a double spark and will therefore be better adapted to ignite a charge 10 even under unfavorable conditions. Further objects and advantages of the invention will appear as the specification proceeds.

The preferred form of my invention is illustrated in the accompanying drawing, in which Figure 1 shows a vertical section through the spark plug; Figure 2 a perspective view of an insulating element having one electrode and another element forming the principal part of my invention connected therewith; and Figure 3 a perspective detail view of the latter element. While I have shown only the preferred form of the invention, I wish to have it understood that various changes or modifications may be made within the scope of the claim hereto attached without departing from the spirit of the invention.

In its main structural features my spark plug does not essentially differ from spark plugs now commonly used, and comprises a metallic shell (1) threaded at its lower end as shown at (2) adapted to be screwed into a registering perforation in the cylinder, not shown in the drawing, and a bushing (3) 35 made of insulating material, preferably porcelain, with a gland (4) threadedly engaging the top of the shell as shown at (6) and bearing on a shoulder (7) of the bushing with an asbestos packing (8) interposed between the gland and the shoulder. The metal shell has a pin (9) extending from its lower end, which latter is bent to extend into the vicinity of the rod (11) extending centrally through the porcelain bushing and 40 projecting from its lower end as shown at (12). The upper end of this rod forms a

terminal to which a wire may be attached between the two nuts (13) and (14). The pin (9) and the lower end of the rod (11) form two electrodes of a circuit including a source 55 of power, the body of the cylinder to which the pin (9) is grounded and a wire connecting the source of power with the upper end of the rod (11). The two electrodes leave a gap between the same across which a spark is caused to jump when a high voltage current is passed through the circuit.

My invention consists in its principal features in the introduction of a third metal element (16) disposed in such a manner as 65 to extend into the gap and to thus form a stepping-stone for the spark so that instead of a single spark two sparks will be produced, one between the electrode (12) and the third element, and the other between 70 the electrode (9) and the third element. The third element may assume many different forms, and the preferred form is shown in the drawing as comprising a loop (17) adapted to engage an annular groove 75 (18) in the insulating bushing from one end of which extends a projection (19) bent as shown at (21) to extend into the gap.

The double spark thus produced will be hotter than a single spark would be and 80 thereby insures proper ignition of a charge of lower grade. An arrangement of this character also allows a good spark to be produced from a comparatively weak source of energy. The electrode (9) might also be 85 omitted and the spark caused to jump from the loop (17) directly to the shell (1).

I claim:

A spark plug comprising an insulating core, a metallic shell carrying the core, a 90 main electrode projecting from the lower end of the core, a second electrode projecting inwardly from the lower end of the shell to a point below and at one side of the main electrode, a metallic loop embracing 95 the core, and a projection on the loop and extending across the lower end of the main electrode to provide a gap between the two and having its free end spaced from the second electrode to form a gap therebetween.

SELDEN S. DAVIS.
